UNITED STATES PATENT OFFICE.

GEORGE A. SCHMIDT, OF NEW YORK, N. Y.

EGG-BEATER.

SPECIFICATION forming part of Letters Patent No. 233,287, dated October 12, 1880.

Application filed September 9, 1880. (No model.)

To all whom it may concern:

Be it known that I, GEORGE A. SCHMIDT, of the city, county, and State of New York, have invented a new and Improved Egg-
5 Beater, of which the following is a specification.

The object of this invention is to provide a more effective and durable device designed especially for use by confectioners, bakers, 10 hotels, &c., when a number of eggs are to be beaten at a time.

The invention consists of two beaters, one revolving in a vertical, and one in a horizontal, plane, supported by a suitable standard 15 and operated simultaneously by suitable gearing, each beater being composed of series or groups of rings of different sizes.

Figure 1 is a side elevation of the device in position, with the containing-vessel in section. 20 Fig. 2 is an end view of the vertically-revolving beater. Fig. 3 is an end view of the horizontally-revolving beater. Fig. 4 is a cross-section on line *x x*, Fig. 1.

Similar letters of reference indicate corresponding parts.

In the drawings, A represents a bed-plate, and B an upright standard firmly secured thereto, provided with a vertical slot, *a*, in which is fitted the lower end of one arm, *b*, of the frame C, which is of the shape of an inverted U, and B' is a thumb-screw, entered through a side of the standard B, to hold said frame C and its attachments at whatever elevation it may be adjusted to. A driving- 30 shaft, D, is passed at right angles through the arm *b*, and has secured on its outer end a crank-wheel, E, and on its inner end a bevel-wheel, F.

Depending from the center of the frame C 40 is a shaft, G, that is held in a vertical plane by passing through a journal-box, H, in the end of an arm, I, which extends inward at right angles from the arm *b'* of the frame C. The shaft B is further secured in place by a collar, K, that encircles said shaft G just above the box H, and is there held by a set-screw, 45 *c*, or other suitable device, and said shaft G has secured on it, below the box H, by a set-

screw, *d*, or other convenient device, a bevel-wheel, L.

On the upper end of the shaft G is secured a bevel-wheel, M, that gears into the wheel F of the driving-shaft D, and on the lower end of said shaft G are secured, by a collar, *f*, having radial lugs *g g*, radial groups, *h h*, of 50 rings, preferably metallic, each group *h* consisting of two or more rings of different diameters, set a little apart from each other, as shown.

On the lower end of the arm *b'* of the frame 60 C, and at right angles thereto, is formed a journal-box, N, that affords a bearing for a horizontal shaft, O, which is held in place by a collar and set-screw, *k l*, respectively, at the outer end of said journal-box N, and by a 65 bevel-wheel, P, which is held by set-screw *m*, or other convenient device on the inner end of said shaft O, and which wheel P gears with the wheel L of the shaft G.

On the outer end of the shaft O is secured 70 a collar, *n*, provided with radial lugs *o o*, each of which carries a radial group, *p*, of three or more rings of different diameters, the rings in each group *p* being set so as to spread apart from each other, as shown.

In operating this device it is designed to introduce the ring-groups *h p* into a vessel, S, containing the eggs and other articles to be operated upon, as shown, and then said ring-groups *h p* are rapidly revolved, the first in a 80 horizontal plane and the last in a vertical plane, by application of power to the crank-wheel E, and during the operation of the device the ring-groups *h* constantly force the material or materials operated upon within reach of the ring-groups *p*, so that a constant circulation of the material or materials is maintained within the vessel S, and every portion thereof is operated upon at whatever velocity said ring-groups *h p* are revolved. When the work is accomplished 85 the thumb-screw B' is slackened and the frame C, with its attachments, is lifted from the vessel S.

Having thus described my invention, I claim as new and desire to secure by Letters Patent—

1. As an improved article of manufacture, an egg-beater constructed substantially as herein shown and described, consisting of frame C, driving shaft and wheel D E, bevel-wheels 5 F L M P, shafts G O, horizontally-revolving ring-groups h, and vertically-revolving ring-groups p, arranged as herein set forth.
2. In an egg-beater, the combination, with

the vertically-revolving ring-groups p p, of the horizontally-revolving ring-groups h h, substantially as herein shown, and for the purpose described.

GEORGE A. SCHMIDT.
